LIFTING APPARATUS

Application filed January 4, 1929, Serial No. 330,314, and in France January 5, 1928.

The present invention is directed to improvements in lifting apparatus.

The primary object of the invention is to provide an apparatus of this character so constructed that railway ties, sleepers and the like can be easily and quickly lifted or released.

Another object of the invention is to provide an apparatus of this kind wherein the ties or sleepers can be handled expeditiously, with a minimum number of workmen.

While the apparatus is primarily designed for use in connection with railway construction work, it is not necessarily limited to such use.

In the accompanying drawings:

Figure 1 is a side elevation of the apparatus.

Fig. 2 is a front view of the same.

Fig. 2^a is a fragmentary detail view.

Fig. 3 is a partial elevation, illustrating the automatic tripping member.

Fig. 4 is a front elevation of a modification of the automatic tripping device.

Fig. 5 is a side view of this modification.

The apparatus comprises a rod 1 having pivotally connected to its inner ends, as at 2 and 2', arms 3 and 3'. The outer ends of the arms are pivotally connected to the inner ends of levers 5 and 5' having annularly disposed terminals 6 and 6' constituting gripping fingers, the purpose of which will appear later. The outer ends of the levers have secured thereto rings 8 and 8' and to which are secured the lower ends of the cables 9 and 9', said cables being so arranged that they may be slackened at times.

To the ends of the rod 1 are secured the lower ends of the normally taut cables 10 and 10', the upper ends thereof being secured adjacent the ends of the frame 11.

The ties or sleepers T to be lifted are provided with sockets 12 and 12' and to lift the same the rod 1 is placed thereabove and the fingers 6 and 6' can then be conveniently placed in the sockets upon slackening the cables 9 and 9'. The frame is then lifted in any approved manner in the direction of the arrow f, whereupon the stress imparted upon the cables 10 and 10' will cause

the fingers to bind in the sockets 12 and 12', as will be obvious. It will, therefore, be noted that upon lifting the frame 11 the ties or sleepers will be likewise lifted.

The frame 11 may then be lowered until the tie rests upon the ground or other support whereupon the cables 9 and 9' will be slackened to enable the fingers 6 and 6' to be conveniently moved from engagement in the sockets.

As shown in Fig. 2^a, the levers 5 and 5' are provided at their inner ends with slots 72 in order that they may be slidably connected with the arms 3 and 3'. By providing the slots 72, the levers may be adjusted axially for engagement with sockets varying in distances apart.

An automatic tripping device is employed and serves to lift the frame 11, the arrangement of the frame being such that a number of ties can be lifted and lowered, as indicated in Figs. 1 and 2, wherein S, S₁, and S₂ indicate positions of the levers 5 and 5' and G₁, G, and G₂ the positions of the fingers.

Owing to the fact that the cables 9 and 9' can be slackened, the ties can be conveniently engaged even if they are not resting in uniform parallel relationship.

The tripping device consists of a socket element 15 in which is slidable an axis 14, said axis being connected with the frame by tie rods 13 and 13'. The socket element has a ring 16 upon its upper end and to which the cables of a suitable lifting mechanism, not shown, may be connected.

The axis is normally held in its uppermost position by an encircling coil spring 17, which rests upon the bottom of the socket element and has a washer 18, which is carried by the axis resting upon its upper end, there being a nut 19 to hold the parts in assembled relationship.

A stud 20 is carried by the socket element and slidably engages in an angular slot 22 formed in the member 21. The slotted end of the member 21 also carries a stud 23 adapted to slidably engage in the longitudinal slot 24 formed in the arm 25 of the T-shaped lever 26, there being a counterweight 27 slidably

adjusted on said lever. The lever is pivoted to the socket element 15, as at 26'.

The member 21 terminates in a depending rod 28 pivotally connected to the arm 29 of an angle lever, the arm 30 thereof having its lower end pivotally connected to the inner ends of the links 33 and 33'. This lever is pivotally supported, as at 31 by brackets 32 mounted on the frame 11.

10 Bell crank levers are pivotally connected to the ends of the frame, as at 36 and 36', the arms 34 and 34' thereof being connected to the outer ends of the respective links 33 and 33'. The upper ends of the cables 9 and 9' are secured respectively, to the arms 35 and 35' of the bell crank levers, as clearly shown in Fig. 2 of the drawings.

Briefly, the operation is as follows:—

20 The gripping fingers 6 and 6' are inserted in the sockets of the tie upon slackening the cables 9 and 9'. The frame 11 is then lifted and as it rises, it consequently would elevate the ties or sleepers. As the ties leave the ground or other support the axis 14 moves 25 downwardly in the socket element 15 and compresses the spring 17. The member 21 and rod 28 move downwardly relative to the socket element 15 so that the slot 22 slides on the stud 20, said stud abutting the upper horizontal wall of said slot, as shown in Fig. 3. Simultaneously the stud 23, sliding in the slot 24 reaches the bottom of the slot and by the action of the counterweight 27, the member 21 is drawn by the stud 23 and is moved 35 laterally, whereupon the stud 20 reaches the end of the upper horizontal part of the slot 22. At this moment the ties being lifted, the member 21 is held stationary by the arm 25, the lifting of the ties then proceeds, and 40 finally the ties are either placed on the ground or on the platform of a wagon. At the time the ties or sleepers touch the ground, the axis 14, being relieved of the weight of the ties, moves upwardly in the socket element 15 by the action of the spring 17, and the member 21 while immobilized on the stud 20, moves 45 downwardly relatively to the frame 11 and tie 13. Due to the movement of the members 29—30, 33—34, and 35, the cables 9 and 9' are pulled upwardly upon movement of the members 33—34' and 35'. The fingers 6 and 6' can then move out of the sockets in the ties. Due to the presence of the axis 36 and 36', the same 55 action is simultaneously produced on the side systems S_1 and S_2 . The disengagement of the fingers from the sockets takes place instantaneously and automatically. Due to the expansion of the spring 17 the fingers 60 automatically move away from the ties as soon as the tie is at rest.

In order that the apparatus is returned to its loaded position, it suffices to actuate, through a handle 37 a cable 38 to which it is 65 attached, to cause the weighted lever to rock,

thus returning the apparatus to its initial position as shown in Figs. 1 and 2.

In the modified form of the invention as shown in Fig. 5, in lieu of the counterweight 27, a small spring 64 is provided and is 70 threaded on a piston 65 having a shoulder 66. The end of the piston is fitted in a member 67 and contacts with a rod 68 slideable vertically with respect to the socket element. The rod 68 is provided at its upper part with 75 a hole 69 in which fits the head of the piston when the rod is in its lowermost position. The rod is, therefore, held stationary and released only if a pull is exerted on the milled knob 70 of the piston.

When the apparatus is under load, the axis 71 moves down in the socket 75 and compresses the spring 78. The rod 68 follows the relative movement of the axis 71. When the object grasped is brought down on the 80 ground or upon any other support, the axis 71 moves upwardly in the socket element, but the rod 68 does not follow, since it is held stationary by the end of the piston engaged in the hole 69. The rod 68 then 85 exerts a pull on the ends of the cables 9 and 9' through the medium of the links 76' and 76'', and 77 and 77', the latter being pivoted as at 78 and 78' on the frame 11. The grasping members engaged with the object can 90 then move apart and the object is released. For returning the device to its initial position, it is only necessary to exert an outward pull on the knob 70, and the jaws of the 95 grasping device close under their own 100 weight, and through the medium of the cables and levers, the rod 68 will rise.

We claim:

1. A device of the class described comprising a rod, an arm pivoted on each end of the rod, levers pivotally and slidably connected to each arm, a grasping means at the end of each lever, a frame, cables connecting the frame and levers, second cables having their upper ends connected with the frame and the lower ends connected with the ends of the rod and means carried by the frame for actuating the first named cable to cause engagement or disengagement of the grasping means with the work.

2. A device of the class described comprising a frame, a rod, a pair of arms pivoted on the rod, a pair of levers pivotally and slidably connected with the arms, a grasping means on the end of each of the levers, taut cables connecting the ends of the rod and frame, second cables connecting the levers, means for lifting the frame, and means pivotally mounted on the frame and connected to the second cables for actuating said levers to cause engagement or disengagement of the grasping means with the work.

3. A device of the class described comprising a frame, a socket element, a pulling axis slideable in the socket element, tie rods

- connecting the frame to the axis, a spring encircling the axis and resting on the bottom of the socket element, a stud on the socket element, a member movable relatively 5 to the stud and having a right angle slot formed therein, a second stud on said element, an armed lever pivotally mounted on said element, one arm of which is provided with a slot in which is guided the second 10 stud, a counterweight on another arm of said lever, a rod rigid with the socket element, a support mounted on the frame, means operable by said rod for actuating the latter levers on said support.
- 15 4. A device of the class described comprising a frame, levers pivotally mounted on the frame, a socket element above the frame, a pulling axis slidable in the socket member, a spring in said socket element encircling 20 the pulling axis, a stud carried by the element, a member having a right angle slot formed therein slidably engaged with the stud, a second stud carried by the socket element, a lever pivotally mounted on the 25 socket element and comprising angularly disposed arms, one arm having a slot therein for engaging the second stud, a counterweight on the other arm of the lever, an angle lever pivotally mounted on the frame, 30 a rod connecting the member and one arm of the angle lever, a rod having grasping levers pivotally and slidably connected with its ends, cables connecting the latter rod and frame, and second cables, the latter cables 35 connecting the levers of the frame and the grasping levers, and means on the frame to give slack to the second cables, as and for the purpose set forth.
5. A device of the class described comprising 40 a socket element having axis slidable therein, a spring in the socket element urging said axis upwardly therein, a stud on the socket element, a member slidable relatively to the socket member and having communicating vertical and horizontal slots therein 45 for slidably receiving the stud, a lever pivotally mounted on the socket element and including angularly disposed arms, one arm of said lever having a slot therein, a second 50 stud carried by the sliding member and slidably engaged in said slot, a counterweight supported by the lever to move the member laterally in one direction to cause the first mentioned stud to engage the horizontal slot 55 of the member upon relative sliding movement of the socket element and axis, and grasping mechanism operable by the slotted member to grasp and release an object upon elevating and lowering the socket element.
- 60 6. A device of the class described comprising a frame, a socket element having a spring restrained pulling axis slidable therein, tie rods connecting the frame and axis, said frame having an angle lever upon its ends, 65 a stud carried by the socket element, a slid-
- ing member having an angle slot therein guided on the stud, a counterbalanced lever pivotally mounted on the socket element and including an arm having a slot therein, a stud carried by the sliding member, said studs slidably engaging the slot of the lever arm, a support mounted on the frame, an angle lever carried by the support, links connecting one end of the latter lever with the angle lever of the frame, grasping means supported below the frame, and flexible connections between the grasping means and said angle levers of the frame.
- 70 7. A device of the class described comprising a rigid frame, a socket element, a pulling axis slidable in the socket element, tie rods connecting the frame and axis, levers pivotally mounted on the frame, a spring in the socket encircling the pulling axis, a member slidable relative to the socket element, a rod carried by said member, links pivotally connecting the levers and rod, work grasping means, cables connecting the frame and work grasping means, second cables connecting the work grasping means and levers, and means associated with the rod for giving slack to the second cable to release the grasping means from the work.
